MATERIAL CHECK

Filed June 9, 1928

UNITED STATES PATENT OFFICE

CHARLES EPSTEIN, OF BROOKLYN, NEW YORK

MATERIAL CHECK

Application filed June 9, 1928. Serial No. 284,040.

This invention relates to devices as applied to fusible, melttable and soluble materials, in bar or block form, to act as a gage indicative of the quantity dispensed.

Proprietors of plumbing establishments, where considerable quantities of solder are used, find it desirable to check the amount of such material issued to their workmen to be used on their jobs, as a precaution and deterrent from pilfering, but up to the present time are unable to do so in a satisfactory manner.

It is therefore an object of the present invention to provide a simple, practical and inexpensive device whereby the number of bars issued may be checked and positively accounted for by the workmen.

A further feature is in the provision of means inseparably combined with such bars as will identify the same and therefore discourage illicit vendition.

These important purposes are accomplished by the novel devices and combinations hereinafter described and illustrated in the accompanying drawing, forming part of this disclosure, and in which:

Figure 1 is a perspective view of a conventional bar of solder showing an application of the invention.

Figure 2 is a partial plan view of a solder bar, broken away to disclose the structure.

Figure 3 is a similar view showing a modified form of the check strip cast in the bar.

Figure 4 is a plan view of a solder bar carrying an adaptation of the check member.

A bar 10 of solder is shown in the several views, but it will be understood that any other materials capable of being molded into bar or block form, as tin, lead, rosin, wax, and like substances, which are melted or consumed in operation, are amenable to the process and protective system herein described.

Disposed lengthwise of the bar, substantially central of its width and thickness, and extending out at one or both ends, is a strip 11 of metal, such as sheet iron, the same bearing on one of its projecting ends 12, a serial number, as at 13, and identification characters 14.

Formed in the longitudinal edges of the

strip are a series of corrugations or notches 15, so that when the mass is molded the strip is held permanently embedded, resisting any attempt at removal.

In the modified form shown in Figure 3 55 a similar strip 11' is provided with an extending end 12' bearing serial numbers, as at 13', the edges of the strip being smooth and unbroken, and in the strip are openings 16 into which the material flows, when melted or in a plastic condition, thus keying the strip permanently within the bar.

In the adaptation of the device shown in Figure 4, there is set in the mold an anchor plate 17 having a tab 18 bearing a serial number 19 and character 20, so that as the material is poured into the mold as to cast the anchor plate rigidly into the bar, the numeral bearing tab extends outwardly from the side.

The ends of the strips or tabs may preferably bear the name of the owner, or at least initials, so that identifications can be made of the bars should occasion occur.

In delivering the bars to a workman, note is made of the serial numbers and the strips or tabs bearing these numbers are to be returned, together with any unused bars, at the completion of the work; obviously this method constitutes a protective system rendering filching of the material well nigh impossible.

While certain preferred embodiments of this device have been shown and described, it will be understood that changes in the form, arrangements, proportions, sizes and details thereof may be made without departing from the scope of the invention as defined in the appended claim.

Having thus described the invention, what is claimed as new and desired to secure by Letters Patent, is:

The combination of a mass of material of predetermined weight with an insert imbedded therein and having an end projecting therefrom, the said end having thereon indicia relating to the mass of material, the said material being of appreciably greater fusibility than the said insert.

In testimony whereof I have hereunto affixed my signature.

CHARLES EPSTEIN. 100
